WRAPPING PAPER ATTACHMENT FOR
SHOW CASESClement V. Hill, Trenton, N. J., assignor to C. V.
Hill & Co., Inc., Trenton, N. J., a corporation of
New Jersey

Application March 21, 1933, Serial No. 661,986

13 Claims. (Cl. 242—55.5)

This invention relates to a wrapping paper attachment for show cases, for supplying wrapping paper in desired amounts from a roll for wrapping up vended goods of various kinds, and the present invention constitutes an improvement upon the construction shown in my prior application filed December 7, 1932, Serial No. 646,185.

In many merchandise stores the available space 10 is so taken up by fixtures and stock that there is no room for the placing of a wrapping paper supply fixture without disposing it in an awkward and inconvenient or obstructing position.

One object of my invention is to provide a 15 wrapping paper supply device which may be applied as an attachment to a show case or counter in such manner as to be in a non-obstructing position and yet in a position to permit ready and convenient removal of the wrapping paper as desired for use.

Another object of the invention is to provide 20 an attachment of this character in which the supply roll may be housed within the show case or counter in an inconspicuous position while a cutter and supporting and guiding means for the free end of the paper sheet are disposed at a 25 point on the exterior of the counter convenient for use without the operator assuming a bending or other awkward posture.

Still another object of the invention is to provide 30 a novel mounting for the supply roll supporting frame which may be swung out of the show case to a position permitting ready removal of a depleted roll and substitution of a new or full roll therefor, together with means for firmly supporting the roll supporting frame in swung-out 35 position.

Still another object of the invention is to provide 40 brackets for attachment to an elevated rear portion of the show case for supporting a delivery roll and a combined brake and cutter, which brackets are constructed in a novel manner to permit application and removal of the supply roll and combined brake and cutter in a ready and 45 convenient manner and without the necessity of detaching the brackets.

Still another object of the invention is to provide 50 a mount for the brackets ensuring attachment of the brackets always in the right position and in accurate alinement to support the delivery roll and combined brake and cutter in exact parallel relation so as to secure a perfect working action of these parts and to prevent binding or other imperfect action in the event that the 55 brackets were attached in a crooked manner.

With these and other objects in view, the invention consists of the features of construction, combination and arrangement of parts, herein-after fully described and claimed, reference being had to the accompanying drawings, in which:

Fig. 1 is an end elevation, partly in section, of a refrigerator show case, to which my invention is shown in the present instance applied, and illustrating the attachment as applied thereto for use.

Fig. 2 is a rear elevation of the structure shown in Fig. 1.

Fig. 3 is a view of parts of the attachment and a part of the show case shown in Fig. 1 on an enlarged scale, and showing in full and dotted lines respectively the supply roll supported in normal position and the position to which it may be swung for removal of an old roll and application of a new one.

Fig. 4 is a sectional elevation taken on line 4—4 of Fig. 3.

Fig. 5 is a horizontal section, on line 5—5 of Fig. 3, through one of the standards of the roll supporting frame.

Figs. 6 and 7 are opposite end elevations of the delivery roll and combined brake and cutter supporting brackets, showing the delivery roll and combined brake and cutter supported thereby.

Fig. 8 is a horizontal section on line 8—8 of Fig. 6.

Fig. 9 is a perspective view of one of the supporting brackets and the adjacent ends of the delivery roll and combined brake and cutter adapted to be mounted therein.

Fig. 10 is a perspective view of the other supporting bracket and a portion of its supporting plate.

Referring now more particularly to the drawings, the numeral 1 designates a show case of any ordinary, conventional or suitable construction, and which, in the present instance, is shown as a refrigerator show case of a well known type. This case is provided with a base compartment 2 having a doorway opening 3 in the lower portion of its rear wall, the upper portion 4 of which wall may form the rear wall of an upper compartment of the show case.

In accordance with my invention, I dispose and house within the compartment 2 a supporting frame 5 for a supply roll, drum or cylinder 6 on which the roll of paper 7 is wound which frame comprises a baseboard or plate 8 from which rise a pair of spaced standards 9 each provided on its inner face with a pair of inwardly extending vertical flanges 10 connected at their lower ends by

60

65

70

75

85

95

100

110

a U-shaped portion 10'. The U-shaped portions 10' form bearings for the end journals of the roll in which said journals may turn or rotate to allow the paper to unwind, while the spaces between the flanges 10 form guide channels or guideways 11 slidably receiving the ends of a metal brake bar 12 which rests upon the upper surface of the paper roll so as to oppose a predetermined resistance to turning of the roll and unwinding of the paper therefrom. The channels also serve as guideways leading to and from the bearings 10' allowing an old roll, i. e., a roll from which the paper has been exhausted, to be easily removed and a new roll to be as readily applied in its place.

The base 8 rests upon the floor 13 of the compartment 2 adjacent to the opening 3, and is hinged at its rear edge, as at 14, to the floor in such manner that the supporting frame and roll 20 may be swung from a normal upright position shown in full lines in Figs. 1, 2, 3 and 4 in which it is housed within the compartment 2, to a horizontal position, as shown in dotted lines in Fig. 3, in which the roll and frame standards extend horizontally outward through the opening in such manner as to permit a roller 6 from which the supply of paper has been exhausted to be removed and a fresh roll substituted in its place, the rolls being readily removable from and applicable to the bearings 10' via the channels 11 when in the latter-named position. By this means an old roll may be removed and a new one substituted in its place without the necessity of inserting and removing rolls through the opening or doorway 3 and without the operator bending over or assuming an awkward and difficult position in order to carry out these operations.

Mounted on the outer sides of the standards 9 are supporting legs 15, each hinged at one end, as at 16, to its standard which normally hang pendent and parallel with the standard when the supporting frame 5 is in normal position. When the frame 5 is swung outward and rearward to the horizontal position shown in dotted lines in Fig. 3, these legs 15 drop by gravity in the swinging action to a vertical position in which they rest on the floor of the room in which the show case is disposed. By this means the frame and the roll will be sustained firmly in the out-swing position and the strain of their weight removed from the hinges 14 and the show case. Stop members 17 and 18 on the standards limit the swing of these legs in opposite directions.

The free end 19 of the paper sheet is conducted from the roll outwardly through the doorway or opening 3 and upwardly alongside the upper rear wall portion 4 on which is mounted a supporting and guide roll 20, this roll 20, and preferably also the paper holding rolls 6, being provided with a peripheral coating or covering 21 of rubber, felt or other suitable material to which the paper tends to adhere and against which the paper frictionally bears to prevent it from slipping. The roll 20 is positioned at a convenient level upon the rear of the counter to enable it and the free end of the paper strip to be manipulated by a clerk or operator in a convenient manner and without the necessity of the clerk stooping or assuming an awkward posture. The extremity of the paper strip is designed to rest upon the top surface of the roller 20 and to be held in contact therewith by a combined cutter and brake member 22, of V-shaped, triangular or inverted trough-shaped form and comprising downwardly diverging front and rear walls 23 and 24 and end

walls 25, said end walls being shorter than the front and rear walls and concavely curved at their lower edges to fit the surface of the roll 20. The member 22 rests by gravity upon the roll or intervening portion of the paper sheet and is of sufficient weight to hold the roll and paper against slippage of the paper or casual rotary movement of the roll, the lower edges of its end walls and the inner face of the lower portion of its front wall forming a friction brake surface holding the roll 16 and portion of the sheet engaged thereby from relative movement. The rear wall 24 of the member 22 also acts in this connection as a stop surface to hold the paper sheet from rearward movement in the event that there is any tendency of the sheet to slip beneath the surfaces of the front and end walls of the member 22. The front wall 23 of the member 22 is designed to serve as a cutter, and to this end its free edge is beveled or sharpened to form a cutting edge 26 along which a desired portion of the sheet which has been pulled forward beyond such edge by the operator may be drawn and thus severed from the remainder of the sheet to supply a wrapping sheet for use.

As shown, the roll 20 and combined cutter and brake member 22 are arranged in superposed and parallel relation and are mounted between and on bracket members 27 and 28 carried by a plate 29 secured by screws or other suitable fastenings 30 to the wall portion 4. The brackets 27 and 28 are respectively provided with flanges 31 and 32 extending outwardly therefrom at right angles thereto. These flanges are provided with bearings and retaining slots 33 and 35 to respectively receive and hold the roll 20 and member 22. The slots 33 which receive and hold the roll 20 are alike in form, and each is inclined upwardly and rearwardly at an oblique angle to the vertical and opens at its upper edge through the rear vertical edge of the flange, said slots forming open bearings receiving the journals 34 at the ends of the roll 20 so as to allow said journals to freely rotate therein. The inclined arrangement of these slots or open bearings 33 provides for the ready removal of a depleted roll from the brackets and ready substitution of a new or filled roll therefor, by removing and applying the rolls at a proper angle of inclination, while the angle at which the slots are formed effectively prevents any casual outward movement and displacement of the roll journals therefrom. The means in the bracket flanges 31 and 32 for receiving and holding the combined brake and cutter member 22 comprises elongated vertical slots 35 and 36, respectively, which receive angular lugs or projections 37 upon the ends of the member 22. The slot 36 is a closed slot, that is, does not open through any of the edges of the flange 32 in which it is formed, while the slot 35, on the contrary, is provided with an oblique extension 38 projecting laterally at an upward and rearward angle therefrom and intersecting its upper portion and opening through the rear edge of the flange 31. This slot extension 38 forms an entrance and exit way allowing the angular lug or projection 37 at one end of the member 22 to be readily inserted into or withdrawn from the slot 35 to enable ready application and removal of the member 22 to and from the bracket members to be effected. In applying the bracket member, it will be understood that the lug 37 at one end thereof is fitted in the slot 36 of bracket 38 and then the lug 37 at the opposite end thereof is inserted into the slot in the other bracket plate 150

80

27 through the opening 38 and the lugs 37 then allowed to drop down into the lower portions of the slots 35 and 36 to dispose the member 22 in proper working position above and upon the roll 5 20 and the paper sheet in contact therewith. The slots 35 and 36 are of such length as to allow the member 22 to have the proper degree of vertical motion to compensate for different thicknesses of paper and to admit of a ready and 10 convenient threading of the free end of the sheet between the member 22 and the roll 20, as well as to admit of the proper angular adjustments of the member 22 with relation to the brackets in applying and removing said member. It will be 15 seen that this construction and mode of mounting the bracket plates adapts the delivery roll and the combined brake and cutter to be readily and conveniently applied to said brackets without detaching the latter from their supporting plate, 20 or detaching the supporting plate from the show case or counter, and also that by the provision of the supporting plate to which the bracket plates are attached in fixed relative positions to each other an accurate positioning of the bracket 25 plates to effect registration of the bearing and keeper slots will be automatically effected upon the application of the bracket plates to their supporting plate, whereby the delivery roll and combined brake and cutter will be mounted for 30 a smooth action and without liability of binding, such as would be liable to occur if the bracket plates were independently attached to the show case or counter. In other words, the use of the supporting plate prevents irregular or crooked 35 mounting of the bracket plates upon a show case or counter which otherwise would be apt to occur, especially when the work is done by inexperienced hands.

It will be understood from the foregoing that 40 upon the placing of a paper roll on its supporting frame 5 within the compartment 6 the free end of the paper sheet may be extended outwardly through the doorway in the form of a feeding strip or portion which may be carried upward and 45 threaded between the roll 20 and member 22, leaving just a sufficient portion of its extremity projecting beyond the cutting edge to be conveniently gripped by the operator, so that whenever desired the required amount of paper may 50 be drawn outward to form the wrapping sheet of required size which is to be severed from the strip. This severing operation is performed, as previously stated, by drawing the projecting portion of the sheet along the cutting edge of the cutter, whereupon the brake surface of the member 55 22 will operate to prevent the roll 20 from turning and/or the free end of the paper strip from sliding backward in rear of the plane of said brake surface, so that the operator may grip the roll 20 and turn it forward to again project the extremity of the sheet beyond the cutter, thus disposing the sheet in preparedness for the ensuing dispensing action. Whenever it is necessary to remove a depleted supply roll and to substitute a new or full roll in its place, this may be effected, as previously explained, by swinging the 60 supporting frame outwardly to dispose it in convenient position to allow such operations to be performed. Also in the event that it should be necessary to apply or remove the dispensing roll and combined brake and cutter, this operation in either case may be effected without disturbing the bracket supporting plate or removing the brackets therefrom.

75 It is to be understood that while the slot 36

is shown as a closed slot, this slot 36 may be made a duplicate in construction of the slot 35, that is to say, each slot 35 and 36 may be provided with an entrance and exit way 38.

From the foregoing description, taken in connection with the drawings, the construction and mode of operation of my new and improved wrapping paper attachment for show cases will be readily understood without a further and extended description and it will be seen that the invention provides an attachment of this character which is readily applicable to counters and show cases in such manner as to be partly housed within the show case or counter and partly disposed upon the exterior thereof so as to occupy but little room space in the store room, and arranged so as to be conveniently operated and disposed so that it will not form an obstruction to free passage and movements of clerks or attendants in serving customers and performing other duties. Also it will be seen that the invention provides an attachment which allows ready removal of supply rolls from which the paper supply is exhausted and substitution of full rolls therefor, and the retention of the free end of the paper strip in position to be readily gripped and severed for the removal of wrapper sheets of the desired sizes whenever required. The invention, furthermore, is of simple construction and may be applied for use at a comparatively low 105 cost.

While the construction disclosed for purpose of exemplification is preferred, it will, of course, be understood that changes in the form, arrangement and details of construction may be varied 110 within the scope of the appended claims, without departing from the spirit or sacrificing any of the advantages of the invention.

What I claim is:—

1. In a wrapping paper attachment for show 115 cases and the like, the combination with a counter or show case having a storage space or compartment provided with an opening in a wall thereof, of a paper roll support normally housed within said space or compartment, means pivotally 120 mounting the support so as to be capable of movement outwardly and inwardly through said opening in the wall of the compartment, a stay mounted on said support so as to be movable to engage a surface to stay said support when moved outwardly through said opening, and means mounted upon the counter or show case at an elevation above the roll support for holding and guiding the paper strip from the roll and severing a portion of the strip from the remainder of the 130 strip.

2. In a wrapping paper attachment for counters, show cases and the like, the combination with a counter or show case having a lower storage space or compartment opening at one side 135 to the exterior thereof, of a paper roll support normally disposed in said space or compartment, means pivotally mounting the support so as to be capable of movement outwardly through said opening, pivotally mounted means upon said support movable to a position to stay the same when moved outward, and means upon the exterior of the counter or show case arranged at an elevation above the support for supporting and guiding the strip from the roll and severing a portion 140 of the strip from the remainder of the strip.

3. In a wrapping paper attachment for counters, show cases and the like, the combination with a counter or show case having a storage space or compartment in the lower portion thereof open- 145

- ing at one side to the exterior thereof, of a paper roll support normally housed in said space or compartment, means pivotally mounting the support in said space or compartment so as to be 5 swung inwardly and outwardly through said opening, means for staying said support when moved outwardly through said opening, and guiding and severing means for the free end of the paper strip mounted upon the exterior of the show case or 10 counter above said support.
4. In a wrapping paper attachment for show cases, counters and the like, the combination with a counter or show case having a storage space or compartment in the lower portion thereof 15 opening at one side to the exterior thereof, of a paper roll support normally housed in said space or compartment, means pivotally mounting the support in said space or compartment so as to be swung inwardly and outwardly through said 20 opening, pivotally mounted means on the support for staying said support when moved outwardly, and a guiding and severing means for the free end of the strip from the roll arranged upon the exterior of the counter or show case above the 25 supply roll.
5. In a wrapping paper attachment for counters, show cases and the like, the combination with a counter or show case having a storage space or compartment in the lower portion thereof opening at one side to the exterior thereof, of a paper 30 roll support normally disposed in said space or compartment, means pivotally mounting the support in said space or compartment so as to be swung inwardly and outwardly through said opening, pivotally mounted stays upon the support to 35 engage a floor and stay the support when moved outwardly, and a guiding and severing means for the free end of the strip from the roll arranged upon the exterior of the show case or counter 40 above the support.
6. In a wrapping paper attachment for counters, show cases and the like, the combination with a counter or show case having a storage space or compartment in the lower portion thereof, of a paper roll support normally disposed in said 45 space or compartment, means pivotally mounting the support in said space or compartment so as to be swung inwardly and outwardly through said opening, stays pivotally mounted at the sides of the support for staying said support when moved outwardly, and a guiding and 50 severing means for the free end of the drawn out strip from the roll arranged upon the counter or show case above the level of the support.
7. In a wrapping paper attachment for show cases, counters and the like, the combination with a counter or show case having a lower storage space or compartment open at the rear thereof, of a paper roll holding support normally housed in said space or compartment, means pivotally mounting the support in said compartment so as to be swung into and out of the same through said opening, means for bracing said 65 support when in outswung position, and means disposed upon the counter above said opening for holding and guiding the paper sheet fed from said supply roll and severing a drawn out portion of said sheet from the remainder of the sheet.
8. In a wrapping paper attachment for show cases, counters and the like, the combination with a counter or show case having a lower storage space or compartment open at the rear thereof, of a paper roll holding support normally 70 housed in said space or compartment, means pivotally mounting the support in said compartment so as to be swung into and out of the same through said opening, braces mounted on said support for movement to rest upon a floor surface and support the outwardly extending portion of the outswung support, and means mounted upon the counter above said opening for supporting and guiding the free end of the paper strip fed from said supply roll and for severing a drawn out portion of the strip from the remainder of the strip.
9. In a wrapping paper attachment for show cases, counters and the like, the combination with a counter or show case having a lower storage space or compartment open at the rear thereof, of a paper roll holding support normally housed within said space or compartment, means pivotally mounting the support in said compartment so as to be swung into and out of the same through said opening, braces mounted on said support for movement to rest upon a floor surface and support the outwardly extending portion of the outswung support, stop means to limit the movements of the braces, and means mounted upon the counter above said opening for supporting and guiding the free end of the paper strip fed from said supply roll and for severing a drawn out portion of the strip from the remainder of the strip.
10. In a wrapping paper attachment for counters, show cases and the like, the combination with means for supporting a paper supply roll so as to permit the paper in strip form to be drawn upwardly therefrom, and supporting and guiding means for the free end of the drawn out strip comprising brackets arranged above said supporting means and each having an inclined bearing slot opening through its outer edge and a keeper slot above the bearing slot, the keeper slot of at least one of the brackets having an entrance and exit opening extending through its outer edge, a delivery roll having end journals to engage said bearing slots, and a combined brake and cutter having end projections to engage said keeper slots.
11. In a wrapping paper attachment for counters, show cases and the like, the combination with means for supporting a paper supply roll so as to permit the paper in strip form to be drawn upwardly therefrom, of supporting and guiding means for the free end of the drawn out strip comprising an attaching plate disposed above said roll supporting means, brackets attached to the plate at fixed relative positions and each having an inclined bearing slot opening through its outer edge and a keeper slot above the bearing slot, the keeper slot of at least one of the brackets having an entrance and exit opening extending through its outer edge, a delivery roll having end journals to engage said bearing slots, and a combined brake and cutter having end projections to engage said keeper slots.
12. In a wrapping paper attachment for counters, show cases and the like, the combination with a counter, of means for supporting a paper supply roll on the counter in such manner as to permit the paper in strip form to be drawn upwardly therefrom, of supporting and guiding means for the free end of the drawn out strip comprising bearing brackets mounted upon the counter above said supporting means, a delivery roll having end journals mounted in the brackets, the journals and bearing brackets

being engageable and disengageable without detaching the brackets from the show case or counter, and a combined brake and cutter vertically movable upon the brackets above the delivery roll and engageable with and disengageable from the brackets without detaching the same from the show case or counter.

13. In a wrapping paper attachment for counters, show cases and the like, the combination with a counter, of means for supporting a paper supply roll within the lower portion of the counter in such manner as to permit the paper in strip form to be drawn therefrom upwardly at the rear of the counter, and support-

ing and guiding means for the free end of the drawn out strip comprising a plate attached to the counter above the roll supporting means, brackets attachable in fixed relative positions to said plate and having bearing slots, a delivery roll journaled in said slots and applicable to and removable therefrom without detaching the same from the plate, and a combined brake and cutter vertically movable upon the brackets above the delivery roll and engageable with and disengageable from the brackets without detaching the brackets from the plate. 80
